UNITED STATES PATENT OFFICE

CHARLES S. GAGE, OF TARRYTOWN, AND CHARLES T. MAEDING, OF ELMHURST, NEW YORK, ASSIGNEES TO LENTHERIC, INCORPORATED, OF NEW YORK, N. Y., A CORPORATION OF NEW YORK.

DESIGN FOR AN ATOMIZER

Application filed October 16, 1930. Serial No. 37,277. Term of patent 7 years.

To all whom it may concern:

Be it known that we, CHARLES S. GAGE and CHARLES T. MAEDING, citizens of the United States, residing, respectively, at Washington Irving Gardens, Tarrytown, New York, and at 8293 Lamont Avenue, Elmhurst, New York, have invented a new, original, and ornamental Design for an Atomizer, of which the following is a specification, reference being had to the accompanying drawing, forming a part thereof.

In the drawing of the atomizer:

Figure 1 is a front view;
Figure 2 is a top view; and
Figure 3 is an end view.

We claim:

The ornamental design for an atomizer substantially as shown.

CHARLES S. GAGE.
